by Geo. H. Lothrop, atty.

UNITED STATES PATENT OFFICE.

PETER E. DE MILL, JR., OF DETROIT, MICHIGAN.

DEVICE FOR HOLDING WRITING-PAPER.

SPECIFICATION forming part of Letters Patent No. 329,291, dated October 27, 1885.

Application filed May 20, 1885. Serial No. 166,184. (No model.)

To all whom it may concern:

Be it known that I, PETER E. DE MILL, Jr., of Detroit, in the county of Wayne and State of Michigan, have invented a new and useful Im-

5 provement in Devices for Holding Writing-Paper, of which the following is a specifica-
tion.

My invention consists in a device for holding blocks of paper, and will be hereinafter
10 fully pointed out in the claim.

Figure 1 is a bottom plan view. Fig. 2 is
a top plan view. Figs. 3 and 4 are sections
on the lines *x x* and *y y*, Fig. 2.

A represents a board or desk-top, which may
15 be of any desired size just large enough to
hold the paper, or large enough to afford working
space outside of the paper. In board A, I
cut a hole a trifle larger than the paper to be
used, and on each side of this hole (not at the
20 top and bottom) I secure a flange, preferably
made of thin metal, F, extending a short distance
over the hole. Usually I make these
flanges somewhat shorter than the hole, as
shown in Fig. 2, and prefer this mode of con-
25 struction. I secure these flanges to the board
by bending the metal down through the sides
of the hole, turning a flange, I, and tacking
this flange to the bottom of the board; but
the flanges F may be secured by being tacked
30 directly to the top of the board A.

B B represent guides secured to the edges of
the hole through board A, and depending below
said board. I generally employ four of
these guides.

35 D represents a piece of board adapted to fit
loosely in the hole in board A.

E represents a block of paper resting on
board D, and with said board D pressed up
against the flanges F by springs C, one end of
40 each of which is secured to the under side of
board A. Four of these springs are shown in
the drawings; but less may be used, if desired.

G represents a thumb-hole cut in board A,
at the bottom of the large hole, to facilitate
taking hold of the top sheet of paper in the 45
block.

H H represent guides similar to B B, at the
bottom of the hole through board A, and may
be used or not, as desired. By depressing
board D against the action of springs C a 50
block of loose sheets of paper may be placed
upon board D, and the action of springs C
when released will press the board D upward
until the upper sheet of paper comes in contact
55 with flanges F, when the paper is held
securely between board D and flanges F, and
may be written upon without being otherwise
held. When the top sheet has been used, by
inserting the thumb at G and taking hold of
60 said sheet with the thumb and finger the sheet
can be readily withdrawn by pulling it toward
hole G, so that it will slide down and out
from under the flanges F. The springs
now raise the board D and secure the next
sheet, as before.

65 This invention may be used as an accessory
to an ordinary desk, or it may be used in po-
sitions where it is necessary to write while
one hand is employed—as, for instance, in
taking memoranda of telephone-messages.

70 What I claim as my invention, and desire to
secure by Letters Patent, is—

The combination, with a board having an
opening formed therein, of the J-shaped plates
75 F, applied to the opposite edges thereof, the
board D lying between said flanges, the springs
C, guides B, and stops H, substantially as de-
scribed.

PETER E. DE MILL, JR.
